UNITED STATES PATENT OFFICE.

ECKFORD BUELL AND JOHN W. LILLEY, OF COLUMBUS, OHIO, ASSIGNEES
TO LOUIS SIEBERT AND JOHN W. LILLEY, OF SAME PLACE.

IMPROVEMENT IN LETTER FILES AND BINDERS.

Specification forming part of Letters Patent No. 140,610, dated July 8, 1873; application filed February 27, 1873.

To all whom it may concern:

Be it known that we, ECKFORD BUELL and JOHN W. LILLEY, of Columbus, in the county of Franklin, State of Ohio, have invented a certain Improved Letter File and Binder, of which the following is a specification:

The first part of the invention relates to the method of placing letters, bills, and invoices, or other papers on file in alphabetical order for preservation and easy reference. The second part of the invention relates to the method of binding the letters or papers when the file is complete.

Figure 1 is a perspective view of the machine when ready for use. Fig. 2 is the divider, hereafter described. Fig. 3 is a plan of the said machine. Fig. 4 is a sectional view at the line A B in Fig. 3.

The machine consists of, first, a base of wood, of any width and length, according to the size of the papers to be filed, C, Fig. 1; second, a metal frame consisting of—

First. Two cross-bars, D and E, Fig. 3, connected together by the side pieces *a* and *a*, the frame being of the same width as the wooden base, and sunk into it so that the surface of the frame is even with the surface of the base, and the cross-bar D is even with the end of the base.

Second. Quadrantal or bracket-shaped side pieces, one straight side fastened firmly to the base even with the edge, and the other perpendicular to the base at its end.

Third. The end gate F, Fig. 1, fastened to the metal frame at the bottom by hinges that allow it to be let down flat even with the base, and when upright held firmly to the side pieces by a spring-latch at each end *d* and *d*, Fig. 1, the one on the opposite end being concealed by the side piece. Across the top of this end gate is a cross-bar, E', Fig. 1. Upon the outside of this cross-bar is a lever, *f* and *f*, Fig. 1, turning on a pivot near the center of the cross-bar worked by a thumb-piece, *g*, and with slanting ends working upon the spring-latches so that when the end of the lever is pressed down by the thumb-piece the latches are opened, and the gate can be let down.

Fourth. In the cross-bar E' at the top of the gate, and an inch, more or less, from each end

of it, are firmly fastened two needles, *i* and *i*, Fig. 1, curved in the shape of a quarter-circle, and extending from the cross-bar of the gate, where they are fastened, downward to the cross-bar E, Fig. 3, of the frame in the base, the points of the needles entering holes *k* and *k*, Fig. 3, in the frame prepared for them. In the cross-bar E, Fig. 3, of the frame, between the two needles just described, and one-third of the whole distance between them, are firmly fastened two other needles, *l* and *l*, Fig. 1, curved in the same arc as the others, and extending from the cross-bar of the frame, where they are fastened, upward in the same direction as the others, and terminating in points about half the distance from the base to the cross-bar of the gate.

Fifth. Behind each of the needles before mentioned, and one-half inch, more or less, from them, is a quadrantal gage, *m m m m*, Fig. 1, each fastened firmly to the cross-bars D and E, Fig. 3.

Sixth. On the cross-bar D of Figs. 1 and 3 of the frame, and between the outside gages and those next within, are metal sockets *n* and *n*, Fig. 1; also, in sectional view, Fig. 4, in which to rest the edge of the divider, hereafter described, when putting paper on or taking it off the files.

Seventh. An ordinary index of Manila or other paper, A, Fig. 1, the same width as the base within the side pieces of the frame, and its length being the distance of the gages from the furthest end of the base. The sheets of the index are pierced by the needles, and lie strung upon them, and held by them firmly against the gages, while the letters of the index are at the opposite end of the base. These gages are for the purpose of guiding the paper, and keeping it straight and even while being placed on the file, as will be more fully described hereafter. The needles are each provided with eyes in their points, the use of which will be hereafter described.

Eighth. A divider of thin board, made thinner at the edge or points, Fig. 2, of the same width as the index, and provided with slots in the edge or point corresponding to the number and depth of the gages, and which allow it to be inserted between the gages as far as

the sockets *n* and *n*, Fig. 1, before described, and in which the points may rest and be held, and allow the other end of the divider to be moved up and down in taking paper off or putting it on the files.

Method of using the machine: First, to put papers on the file, insert the divider between the leaves of the index at the proper letter of the alphabet, and push the divider through till its points rest in the sockets before mentioned; then raise the handle of the divider till all the leaves of the index and papers on file above the divider are thrown off from the two short needles and are only held by the two long ones, and pressed with the divider, then let down against the end-gate, still keeping the leaves thrown off pressed against it with the divider to keep them from falling back or leaning; then place the end or side, as desired, of the sheet to be filed against the gages and on the points of the shorter needles; then insert the points of the divider in the sockets above the sheet to be filed, and with the divider, using the sockets as a fulcrum, press the sheet down to its proper place on the file; then throw up the end-gate till it is fastened by the spring-latches. This brings the long needles down to the base, piercing with these needles, likewise, the sheet just filed upon the others, and, with the divider, press the portion of the index and the sheets filed that were thrown off at first back to their place, as at first. This completes the operation of filing, and, with a little practice, can be done very quickly.

Second. To take a sheet from the files: This will be readily suggested from the process of putting a sheet on the file just described.

Third. To bind the file: First thread the two short needles with a piece of small strong twine; then, with the divider, throw the index and papers filed off from the short needles onto the long ones, and let down the end-gate. This pulls the cord through the two middle holes in the file of papers in the shape of a loop. Then draw the ends of the cord through the holes in the file of papers and out from the

eyes of the two needles; then with the end of the cord nearest the left hand thread the left-hand long needle; the same with the right; then close the end-gate, and, with the divider, press the file of papers back to their place on the base, and, keeping them in that position, let down the end-gate. This pulls the cords through the end holes in the shape of a loop. Then pull the ends of the cords through the holes and out from the needles; then, with the left-hand cord, thread the left-hand short needle, and the same with the right; then with the divider, the end-gate being down, throw the file of papers off from the file altogether; then pull the ends of the cord out from the middle holes and out of the short needles, and tie the ends tight to the file of papers, and the operation is completed, and the file of papers is ready to be laid away in a convenient shape for reference. A new index may then be placed upon the file, and the machine used again. The file of papers may also be bound, by the same process, in a cover prepared for it.

We do not claim the index as our invention; but—

We claim as our invention—

1. The disposition of needles of different lengths in a paper file and binder in a manner relative to each other and to the cross-bar *E* of the frame, and the cross-bar *E* of the end-gate, and to the other devices therewith connected, whereby individual papers or folios are detachable without deranging the remaining papers filed, substantially as set forth and described herein.

2. The combination and arrangement of the base *C* and metallic frames *D E*, the bracket-shaped sides *b b* and *c c*, the end-gate *F*, the gages *m*, *m*, *m*, and *m*, the needles *i i* and *l l*, and the divider, Fig. 2, operating together substantially as and for the purpose herein shown.

ECKFORD BUELL.
JOHN W. LILLEY.
